(57) **CLAIM**

The ornamental design for a lifetime golf shoe spike wrench, as shown and described.

DESCRIPTION

FIG. 1 is a perspective view for a lifetime golf shoe spike wrench with the end installed in the main body showing my new design;

FIG. 2 is a perspective view with the end wrench removed from the main body thereof;

FIG. 3 is a right side view thereof, the left side view being a mirror image thereof;

FIG. 4 is a front view thereof;

FIG. 5 is a sectional view taken along lines 5-5 from FIG. 4 thereof;

FIG. 6 is a back view thereof;

FIG. 7 is a top view thereof;

FIG. 8 is a bottom view thereof; and,

FIG. 9 is a perspective view thereof shown in an environment of use.

The broken lines in FIG. 9 depict environmental subject matter of a golf shoe and form no part of the claimed design.
